UNITED STATES PATENT OFFICE.

HOSEA W. LIBBEY, OF BOSTON, MASSACHUSETTS.

TELEPHONING FROM CARS IN MOTION.

SPECIFICATION forming part of Letters Patent No. 596,276, dated December 28, 1897.

Application filed April 6, 1897. Serial No. 630,925. (No model.)

To all whom it may concern:

Be it known that I, HOSEA W. LIBBEY, a citizen of the United States, and a resident of Boston, in the county of Suffolk and State of Massachusetts, have invented certain new and useful Improvements in Telephoning from Cars in Motion, of which the following, taken in connection with the accompanying drawings, is a specification.

10 My invention relates to means for telephoning from a railroad-car while in motion to any desired point or station.

The invention consists in the arrangement and construction of the connections between 15 the telephone and an electric supply and in the means for completing the circuit so as to transmit a message from the car to any desired point or station, as hereinafter described, and pointed out in the claims.

20 Referring to the accompanying drawings, Figure 1 represents a portion of a railroad-car fitted with a telephone and the connections for making a circuit whereby a person can telephone from the car while in motion 25 to any point or station. Fig. 2 is a transverse section of same. Fig. 3 is a sectional view of a rail, a portion of one of the wheels fitted with two contact-rings, and a rail for supplying the electric fluid and a return-rail for 30 carrying off the same. Fig. 4 is a sectional view of the road-bed and rails, showing how the electric current may be supplied from one side and carried off on the other.

A represents the body of a car, B the truck, 35 C C' the wheels, and D the axles, all of which may be of ordinary construction except the wheel C', which wheel is provided with suitable contact-rings. I prefer to construct the wheel C' with two contact-rings E E', of copper or other suitable material, as shown in Fig. 3, in which the edge of the flange of the wheel is formed with a half-round groove or 40 recess c, that is lined with a suitable insulating material c', and a ring or hoop E, of copper or other good conductor, sprung or otherwise secured therein, and to the inner edge 45 of the flange is secured a flat ring or hoop E', of copper or other good electric conductor, said ring being insulated from the wheel by 50 any suitable insulating material.

In connection with wheels thus constructed to convey and return the electric current I

employ two bars or rails F F', of copper or other suitable conducting material, that are carried in the upper ends g of forked springs 55 G, the lower ends of which are secured to the web of the rail H in any suitable manner, the bars F F' being insulated from the forked ends of said springs. I I' are trolleys. One, I, runs upon the ring E in the flange of the 60 wheel C', and the other, I', runs upon the ring E' on the inner side of the flange. To the trolley I, that supplies the electric current from the inner rail F, is attached a wire J, that leads to a telephone K, the return- 65 wire L of which connects with the trolley I', that runs upon the ring or hoop E', secured to the inside of the flange of the wheel, which ring or hoop E' is in contact with the rail F', to which wires M are attached at the required 70 points to connect with a telephone at any station on the line or to a telephone at the terminal.

Instead of having two rails F F' side by side they might be arranged one on either side of 75 the track, as shown in Fig. 4, in which case both of the wheels C' would have to be formed with rings E in their flanges, or rings E' may be secured to the side of said flanges, only one connection on each side being required. 80

Supposing the rail F, which carries the battery-current and sound-waves to the telephone on the car, and the rail F', which carries the current and sound-waves from the telephone on the car to telephones at stations connected 85 therewith and from thence to ground, were arranged side by side, as shown in Fig. 3, the electric current would be supplied through the rail F, then pass through the ring E in the edge of the flange of the wheel C' and be taken off by 90 the trolley I, and thence conducted through a wire J to the telephone K, the circuit being completed when the telephone is in operation by the wire L, passing to the trolley I', thence to the ring or hoop E' on the side of the flange 95 of the wheel C', and pass to the rail F', from which it is carried by wires M to any desired point or station.

In cases where it is found desirable to have the supply and return rails on opposite sides 100 of the track, as shown in Fig. 4, of course, only one electric rail F' would have to be supported on each side by the springs G', and either the ring E in the flange of the wheel or the ring

E' on said flange might be employed for making the contacts with said rails.

What I claim is—

1. In a railroad a wheel having a ring of conducting material let into the edge of its flange but insulated therefrom and a ring of conducting material attached to the inner side of the flange but insulated therefrom substantially as and for the purposes set forth.
2. In a railroad two electric rails carried by springs secured to the web of the rail, a wheel or wheels having rings of conducting mate-

rial in or on its flange, trolleys running upon said rings in combination with a telephone and connections between the telephone and 15 trolleys substantially as set forth.

In testimony whereof I have signed my name to this specification, in the presence of two subscribing witnesses, on this 27th day of February, A. D. 1897.

HOSEA W. LIBBEY.
